Primary Examiner — Katherine A Holbrow(74) *Attorney, Agent, or Firm* — Armstrong Teasdale LLP(57) **CLAIM**

We claim the ornamental design for a display screen or portion thereof with a graphical user interface, as shown and described.

DESCRIPTION

FIG. 1 is a front view of a first embodiment of a display screen or portion thereof with a graphical user interface showing the new design;

FIG. 2 is a front view of a second embodiment of a display screen or portion thereof with a graphical user interface showing the new design;

FIG. 3 is a front view of a third embodiment of a display screen or portion thereof with a graphical user interface showing the new design; and,

FIG. 4 is a front view of a fourth embodiment of a display screen or portion thereof with a graphical user interface showing the new design.

The outermost broken line illustrates a display screen or portion thereof and forms no part of the claimed design. The remaining broken lines represent elements of the display screen or portion thereof with a graphical user interface that form no part of the claimed design.

1 Claim, 4 Drawing Sheets(56)
